UNITED STATES PATENT OFFICE.

CLARENCE G. WING, OF CLEVELAND, OHIO, ASSIGNOR TO THE SCOTT-ULLMAN COMPANY, OF CLEVELAND, OHIO, A CORPORATION OF OHIO.

DESIGN FOR A LIGHTING FIXTURE.

Application filed March 23, 1925. Serial No. 12,817. Term of patent 3½ years.

To all whom it may concern:

Be it known that I, CLARENCE G. WING, a citizen of the United States, residing at Cleveland, in the county of Cuyahoga and State of Ohio, have invented a new, original, and ornamental Design for a Lighting Fixture, of which the following is a specification, reference being had to the accompanying drawing, forming part hereof, wherein—Fig. 1 is a side elevation and Fig. 2 is a bottom plan view of a lighting fixture exhibiting my new design.

I claim:—

The ornamental design for a lighting fixture, as shown.

CLARENCE G. WING.
